INVENTOR.

Willard Jefts

United States Patent Office.

WILLARD JEFTS, OF BATTLE CREEK, MICHIGAN.

Design No. 3,004, dated April 21, 1868.

DESIGN FOR THE LEGS OF A TABLE.

The Schedule referred to in these Letters Patent and making part of the same.

TO ALL WHOM IT MAY CONCERN:

Be it known that I, WILLARD JEFTS, of Battle Creek, in the county of Calhoun, and State of Michigan, have originated and designed a new style of Fluting for Table-Legs, Columns, &c., of which the following is a full, clear, and exact description, reference being had to the accompanying drawings, and to the letters of reference marked thereon, and being a part of this specification.

Figure 1 is a perspective view of a table-leg finished according to my design.

Figure 2 is a sectional view upon the line X X in fig. 1.

The same letters indicate like parts in each figure.

A is the shaft, B the base, supporting the shaft, and the capital C. The shaft A is provided with semi-circular fittings 2, around its periphery, parallel with its centre, and equally divided in space in the circumference of the same. Next above the fluted part of the shaft is a beaded projection, 4, also fluted in the same manner as the shaft.

I am aware that a fluting is sometimes used upon furniture-legs, but it is generally a shallow concave fluting, and entirely different from the one I describe, which is cut into the wood, one-half the depth of a given circle, measuring from the circumference of the leg.

What I claim as my invention, and desire to secure by Letters Patent, is—

A design or pattern for table-legs, as herein set forth and shown.

WILLARD JEFTS.
